UNITED STATES PATENT OFFICE.

HARBERT K. FORBIS, OF DANVILLE, ASSIGNOR TO HIMSELF AND GEORGE F. LUPTON, OF GEORGETOWN, KENTUCKY.

THILL-CO尤PLING.

SPECIFICATION forming part of Letters Patent No. 247,897, dated October 4, 1881.

Application filed August 19, 1881. (Model.)

To all whom it may concern:

Be it known that I, HARBERT K. FORBIS, of Danville, in the county of Boyle and State of Kentucky, have invented a new and Improved Thill-Coupling, of which the following is a full, clear, and exact description.

The object of my invention is to provide a new and improved thill-coupling which is so constructed that the thill will be held firmly to the shaft and coupling and uncoupling of the thill is greatly facilitated.

The invention consists in an angular thill bolt or pintle the free end of which rests against the axle and is locked on the same by a spring-latch on the axle.

In the accompanying drawings, Figure 1 is a perspective view of my improved thill-coupling, parts being shown in section. Fig. 2 is a cross-sectional elevation of the same. Fig. 3 is a longitudinal sectional elevation of the spring-latch.

Similar letters of reference indicate corresponding parts.

The eye A at the end of the thill B fits in between the jaws C of the clip D, held on the axle E in the ordinary manner by means of a strip, F, and bolts G. The bolt or pintle H is passed through the apertures in the jaws C and through the eye A, and an angular arm, J, of this bolt H rests against the axle E and is held against the same by a sliding bolt, K, surrounded by a spiral spring, L, contained in a casing, M. The end of the bolt K holding the arm J is beveled from the upper to the lower edge, and the other end of the bolt is provided with a knob, N. A transverse strip, O, of the casing L passes through a longitudinal slot, P, of the bolt and prevents this bolt from turning. The casing M is attached to a rounded strip, Q, fastened to the axle E.

If the thill B is to be removed, the bolt R is drawn in the direction of the arrow a', so as to release the arm J, which is turned in the direction of the arrow b', upon which the bolt H is withdrawn.

To fasten the thill to the axle, the bolt H is

passed through the apertures in the jaws C and through the eye A, and the arm J is turned in the reverse direction of the arrow b' until it strikes the end of the bolt K. If the arm J is pressed against the beveled end of the bolt, this bolt will be pushed in the direction of the arrow a', and when the arm J rests against the axle the bolt will snap forward over it in the inverse direction of the arrow a' and will hold the arm J against the axle, thus locking the bolt in its position in the eye A and the aperture in the jaws C. The thill is thus held firmly to the axle, can be coupled or uncoupled very readily and conveniently, and cannot become uncoupled accidentally. The jaws C are connected by a strip, S, at their lower edges, whereby a box for the eye A is formed.

Having thus fully described my invention, what I claim as new, and desire to secure by Letters Patent, is—

1. A spring-latch, in combination with the angular bolt of a thill-coupling, substantially as herein shown and described, and for the purpose set forth.

2. In a thill-coupling, the combination, with the jaws C, the eye A, and the angular bolt H, of the spring-latch bolt K on the axle, substantially as herein shown and described, and for the purpose set forth.

3. In a thill-coupling, the combination, with the jaws C, the eye A, and the angular bolt H, of the bolt K, the spring L, and the casing M, attached to the axle E, substantially as herein shown and described, and for the purpose set forth.

4. In a thill-coupling, the combination, with the jaws C, the eye A, and the angular bolt H, of the catch K, the spring L, the casing M, and the cross-piece O, passing through a longitudinal slot, P, in the bolt K, substantially as herein shown and described, and for the purpose set forth.

HARBERT K. FORBIS.
